UNITED STATES PATENT OFFICE.

WILLIAM C. BORGERT, OF STURGIS, MICHIGAN, ASSIGNOR TO JERBOLD F. WALTON, OF STURGIS, MICHIGAN.

ADJUSTABLE CHAIR.

1,087,526.

Specification of Letters Patent. Patented Feb. 17, 1914.

Application filed December 21, 1912. Serial No. 738,054.

To all whom it may concern:

Be it known that I, WILLIAM C. BORGERT, a citizen of the United States, residing at Sturgis, Michigan, have invented certain 5 new and useful Improvements in Adjustable Chairs, of which the following is a specification.

This invention relates to improvements in adjustable chairs.

10 The main objects of this invention are: First, to provide in an adjustable chair, an improved means for adjustably supporting the back. Second, to provide in an adjustable chair an effective means for adjusting the back which may be readily controlled by 15 means of a push button device and which is substantially noiseless in its operation. Third, to provide in a chair having an adjustable back, an improved adjusting mechanism which effectively supports the back against movement in either direction, and at the same time, is easily released and adjusted. Fourth, to provide in an adjustable chair, an improved means for adjustably supporting the back, which is effective for 20 the purpose and at the same time quite simple in its parts and the assembling of the parts, and very durable.

Further objects, and objects relating to 25 structural details, will definitely appear from the detailed description to follow.

I accomplish the objects of my invention by the devices and means described in the following specification.

30 The invention is clearly defined and pointed out in the claims.

A structure which is a preferred embodiment of my invention is clearly illustrated in the accompanying drawing forming a 35 part of this specification, in which:

Figure I is a bottom perspective view of a structure embodying the features of my invention. Fig. II is a detail inverted plan of the structure shown in Fig. I. Fig. III is a bottom view of the supporting plate 7 with the spring 27 mounted thereon. Fig. 40 IV is a detail perspective view partially in section, on a line corresponding to line 4-4 of Fig. II. Fig. V is a detail vertical section on a line corresponding to line 5-5 of

Fig. II. Fig. VI is a detail view, partially in section, on a line corresponding to line 6-6 of Fig. III, showing the mounting for the spring 27. Fig. VII is a detail perspective view similar to that of Fig. IV, of a 55 modified structure.

In the drawing, similar reference characters refer to similar parts throughout the several views, and the sectional views are taken looking in the direction of the little 60 arrows at the ends of the section lines.

Referring to the drawing, the chair frame illustrated consists of the rear posts 1 and front posts 2 which are extended to form the front and rear legs of the chair. 65 On the upper ends of the posts are arms 3. The posts are connected by the side frame pieces 4 and the front and rear frame pieces 5 and 6, respectively. The frame is also provided with a horizontal frame piece 7 on 70 which the mechanism for adjustably supporting the back is mounted.

The back 8 is pivotally mounted between the rear posts 1. The pivots are not shown, as their arrangement will be readily understood. The back is provided with a downwardly projecting arm 9 which projects through the slot 10 of the horizontal frame piece 7. The arm 9 is connected by the link 11 to the sliding bar 12. The sliding bar 12 80 is slidably supported in a way 13 formed in the upper side of the block-like member 14. The member 14 is mounted on the under side of the supporting plate 15 by the rivets 16. The screws 16, in the structure illustrated, assist in securing the member 14 to the plate and also in securing the plate to the frame piece 7. Additional securing 85 screws 17 are provided for the plate. The member 12 is thus slidably supported 90 against the under side of the plate 15. The slide 12 is provided with downwardly projecting ears 18 to which the link 11 is pivoted. The plate 15 is provided with stop lugs 19 for limiting the rearward movement 95 of the member 12. Coiled springs 20 are connected to the ears 18 and to the rear frame piece 6 and tend to return the back to its forward position. The slide 12 is provided with series of holes 21 serving as 100

seats for the clutch ball 22. The member 14 is provided with a chamber 23 for the ball 22, the chamber opening into the way 13 for the slide 12. See Fig. V. The ball seats or 5 the holes 21 are preferably conical and the chamber 23 is of such diameter that, while the ball drops freely from the seat when the ball actuating member 24 is retracted, it is effectively supported against lateral movement. The ball actuating member 24 is supported in a slide-way 25 extending through the ball chamber 23 and transversely of the 10 way for the member 12. The actuating member 24 is provided with a cam 26 on 15 which the ball travels.

When the actuating member 24 is pushed inward or actuated, the ball is raised into engaging position and supported in engaging position until the member 24 is retracted, when the ball drops down and releases 20 the member 12 and permits the adjustment of the back.

The spring is mounted on the plate 15 by engaging its laterally turned end 29 in a 25 hole in the plate, and with the lug 30.

The actuating member 24 is connected by the pivot 31 to one arm of the bell crank lever 32 which is mounted on one of the frame side pieces by means of the bracket 30 33. The lever 32 is actuated by the push rod 34 connected to its other arm of the lever, the push rod being extended up through one of arms 5 of the chair. With the parts thus arranged, when the push rod is 35 moved downwardly, the actuating member 24 is withdrawn or retracted, permitting the ball to drop from its engaging position and thus releasing the back. When the push rod is released, the actuating member raises 40 the ball and supports it in its engaging position.

By providing the slide 12 connected to the back, with ball seats, the ball very effectively and securely engages the same and 45 also readily releases or disengages when the actuating member for the ball is retracted.

In the modification shown in Fig. VII, the ball actuating member 35 is actuated by the coiled spring 36, one end of which is connected by the screw eye 37 to the ball holder member 14. The cam 38 of this member 35 is formed by a bend or offset in the bar. The operation of modification is the same as that of the structure shown in the other 55 figures.

The operation of the device embodying my improvements is very simple and is, as stated, substantially noiseless. At the same time, the mechanism is very secure. The 60 parts are simple in structure and easily assembled and easily mounted on the chair.

I have illustrated and described my improvements in detail in a form which I

have found satisfactory. I am aware that there are various modifications possible other than the one I have illustrated, but I have not attempted to illustrate or describe such modifications herein as I believe the disclosure made will enable those skilled in the art to apply my improvements as conditions 65 may require. I desire, however, to be understood as claiming my improvements specifically in the form illustrated as well as broadly within the scope of the appended claims.

Having thus described my invention, what I claim is new and desire to secure by Letters Patent is:

1. In a chair, the combination with the frame and adjustable back, of an arm connected to said back, a slide with a series of ball seats, a clutch ball coacting with said bar, a supporting plate mounted on the chair frame, a ball holder member mounted on the under side of said supporting plate 80 and having a way for said slide, a ball chamber opening into said way and a cam way disposed transversely of said slide way and opening into said ball chamber, a movable bar-like ball actuating member having 85 a cam thereon arranged in said cam way to raise and support said ball in its engaging position, said ball being adapted to drop into said chamber out of engagement with said slide when the cam is retracted, a spring 90 arranged to act on said ball actuating member to normally retain the same in its actuated position, a bell crank lever to which said ball actuating member is pivotally connected, a supporting bracket for said lever, 100 and a push rod connected to said lever.

2. In a chair, the combination with the adjustable back, of a horizontal slide having ball seats therein, connected to said back, a clutch ball coacting with said slide, a ball 105 holder member provided with a ball chamber below said slide, and a movable cam member disposed beneath the clutch ball adapted to raise and support said ball in its engaging position said ball being adapted to 110 drop into said chamber out of engagement when the actuating member is retracted.

3. In a chair, the combination with the adjustable back, of a slide with a series of ball seats connected to said back, a clutch 115 ball coacting with said slide, a ball holder member provided with a ball chamber, a movable cam member adapted to support said ball in its engaging position, and a spring arranged to act on said cam member to normally retain the same in its actuated position.

4. In a chair, the combination with the adjustable back, of means for adjustably supporting said back, comprising a member 125 having ball seats therein, a clutch ball

coacting with said member and a movable cam member adapted to support said ball in its engaging position, a spring to retain the same in engagement, and a manually operated means for withdrawing said cam member.

In witness whereof, I have hereunto set

my hand and seal in the presence of two witnesses.

WILLIAM C. BORGERT. [L.S.]
